Term of patent 14 years

(Cl. D58—13)

FIG. 2

FIG. 3

FIG. 1 is a three-quarter perspective view of a display tray embodying my design, the lid portion of the tray being shown in open condition;

FIG. 2 is a top plan view thereof on an enlarged scale, the lid portion being shown in closed condition;

FIG. 3 is a front elevational view of the tray of FIG. 2;

FIG. 4 is a bottom plan view thereof;

FIG. 5 is an end view thereof taken from the left hand end of FIG. 2; and

FIG. 6 is an end view thereof taken from the right hand end of FIG. 6.

The dominant features of the design reside in the full line portions of the drawing.

I claim:

The ornamental design for a display tray, as shown and described.
